UNITED STATES PATENT OFFICE.

ROBERT JOHN LYLE, OF KINMOUNT, ONTARIO, CANADA.

TROLLEY SHOE AND HARP THEREFOR.

Application filed December 5, 1925. Serial No. 73,475.

My invention relates to improvements in trolley shoes and harps therefor, and the object of the invention is to provide a shoe or sliding contact which will work successfully for city service as well as on rural lines and which will have two relatively long, straight contact surfaces for forward service and a short contact surface for reverse service, and which will at the same time be economical to manufacture, simple and "fool proof" in construction and produce reliable results, and it consists essentially of the arrangement and construction of parts as hereinafter more particularly explained.

Fig. 1 is a side elevation of my trolley shoe and harp shown in contact with the trolley wire.

Fig. 2 is an elevation looking edgewise at the shoe.

Fig. 3 is a sectional view through the shoe and harp showing it in the initial position it assumes when engaging the trolley wire.

Fig. 4 is a similar view to Figure 3 showing the shoe in the position it assumes during the forward service.

Fig. 5 is a similar view to Figure 4 showing the position the shoe assumes during reverse service.

Fig. 6 is a sectional view through the shoe showing a modified form of contact surface.

In the drawings like characters of reference indicate corresponding parts in each figure.

1 indicates a shoe which is pear shaped in general form and provided in the body thereof with a longitudinally extending slot 2 having semi-circular ends 3 and 4. The apex end of the pear shaped body of the shoe is semi-circular as indicated at 4^x, and concentric with the centre of the end 3 of the slot 2. The end 5 forming the base of the pear shaped body is also formed concentric with the centre of the slot end 3, the ends of the base portion 5 curving at 6 and 7 to merge into the inclined sides 8 of the body.

By this construction it will be seen that a substantially pear shaped body is formed in which the longitudinal slot 2 is located in relatively close proximity to the apex or small end 4 of the body.

The body 1 is provided with a surrounding peripheral groove 9 comprising the straight portions 10 and 11 forming straight contact surfaces which are alternately used as contact surfaces engaging the trolley wire 12 during forward movement. That is to

say when one surface such as 10 becomes worn the shoe is removed and reversed so as to use the surface 11 in the same relative position to the trolley wire 12. Normally the shoe assumes the balanced position shown in Figure 3. When brought into contact with the trolley wire 12 which engages the contact surface 10 or 11 at the large end of the shoe body, such large end is depressed by the upward pressure of the trolley pole carrying the parts into the position shown in Figure 4, with the trolley wire engaging the long contact surface 10 or 11.

13 is a trolley harp provided with a cross pin or axle 14 which extends through the slot 2 of the shoe body 1, assuming the position at the forward end of the slot 2 during the forward operation of the shoe, but when, however, reverse operation is required and when the car starts to back up the axle pin 14 extending through the harp slides back in the slot 2 and strikes the opposite end of the slot, forcing the shoe to turn on its pivot and tip over with the slight jar thus caused to its vertical reverse position, or the position shown in Figure 5, the pin 14 assuming the position indicated in this figure at the opposite end of the slot 2. This jar produced by the backing up of the car also starts the shoe on its slide along the trolley wire.

The difficulty with most sliding contacts and their failure to satisfactorily slide in reverse is first, a long contact surface and second a contact which is used both for forward and reverse service. When a long contact is used for forward service a groove is cut in it by the action of the trolley wire thereon rendering the surface unsuitable for satisfactory use in reverse, particularly if the trolley wire is at all slack, or the trolley pole angle rather vertical or the tension strong.

The short surface provided at the small end of the shoe as at 4^x is little used, and used exclusively for back-up, or reverse movement and will remain smooth and furnish most reliable back-up or reverse sliding contact. It is for the purpose of overcoming the difficulty heretofore encountered in this class of shoe that the shoe above described has been designed which provides long contact surfaces for engagement during the forward movement and which are therefore relatively long lived, and the short contact surface for reverse movement which is com-

paratively little used, and therefore does not require the same length of life as the surfaces used during forward movement, providing a separate surface for reverse instead of using a surface which is normally used for forward movement and which has a tendency to become worn and grooved and unfit for reverse contact.

15 and 16 are stop projections formed on a face of the shoe body 1 and coact with the projection 16^x of the stop rib 16. 17 is a rib formed on the opposite side of the harp so that when the shoe is in position in the fork of the harp the ribs 16 and 17 bear against the opposite faces of the shoe body so as to definitely hold it in position, the projections 16^x coacting alternately with the projection 15 during forward movement and with the projection 16 during reverse movement.

29 In Figure 6 I have shown the centre portion of the shoe at the base of the surrounding groove provided with a supplemental groove into which is slipped a member 18 of relatively harder metal than the body of the shoe, such strip being provided with lugs 19 fitting into recesses 20 and secured therein by rivets 21 extending therethrough and through the shoe.

What I claim as my invention is:

30 1. In a three contact sliding trolley shoe and harp therefore, the combination with the harp fork and axle pin extending therethrough, of a shoe body substantially pear shaped in general form and through which the axle pin extends in proximity to the small end of the body and having a surrounding peripheral groove extending in di-

verging lines from the small to the large end of the shoe body end forming three wire engaging surfaces, one of which is at each side of the body and operable during the forward travel of the shoe, and the remaining contact surface across the small end of the body into which the aforesaid straight surfaces merge and which furnishes a reverse or back-up contact surface during the reverse movement of the shoe.

2. In a three contact trolley shoe and harp therefore, the combination with the shoe body substantially pear shaped in general form and having a surrounding peripheral groove extending in diverging line from the small end to the large end of the shoe body and a harp into which the body is pivotally mounted adjacent its small or narrow end, coacting stop means on the shoe and harp for limiting the pivotal movement of the shoe body in the harp.

3. In a three contact trolley shoe and harp therefore, the combination with the harp fork and axle pin extending therethrough, of a shoe body substantially pear shaped in form and having a slot formed therein to receive the axle pin adjacent the small end of the body and having semi-circular ends, the small and large ends of the shoe being formed concentric to the centre of the slot end adjacent the small end of the shoe and provided with a surrounding peripheral groove extending in diverging lines from the small end to the large end of the shoe body forming wire engaging contact surfaces on each side end at the small end of the shoe.

ROBERT JOHN LYLE.
